UNITED STATES PATENT OFFICE.

WILLIAM W. DAVIS, OF SHILOH, NEW JERSEY.

CRATE AND OTHER RECEPTACLE.

No. 825,893.

Specification of Letters Patent.

Patented July 17, 1906.

Application filed March 28, 1905. Serial No. 262,509.

To all whom it may concern:

Be it known that I, WILLIAM W. DAVIS, a resident of Shiloh, in the county of Cumberland and State of New Jersey, have invented 5 certain new and useful Improvements in Crates and other Receptacles; and I do hereby declare the following to be a full, clear, and exact description of the invention, such as will enable others skilled in the art to which 10 it pertains to make and use the same.

The invention relates to crates and other receptacles, and has for its object to provide a strong economically-practical receptacle having an easily-removable cover adapted when 15 in use to stiffen the receptacle and also to provide such receptacle and cover with a simple and efficient pivoted connection.

The invention consists in the construction hereinafter described and pointed out. 20 In the accompanying drawings, forming part of this specification, Figure 1 is a side view of the receptacle. Fig. 2 is an end view of the same. Fig. 3 is a partial perspective of crate, cover, and connection. Fig. 4 is a 25 similar view of a modification. Fig. 5 is a partial end view of another modification, showing in dotted lines the cover in open position. Fig. 6 is a section on line 6 6 of Fig. 5, a P-staple pivot being shown partially inserted. Fig. 7 is a similar view, the staple-pivot being entered in an operative situation; and Fig. 8 is a section on line 8 8 of Fig. 4.

The sides of the crate each consists of the 35 slats 1, fixed to posts 2. The ends of the crate each consists of the slats 2, three in number in the present instance. The outer slats 2 constitute the posts mentioned. The bottom consists of slats 3, which are longer 40 than slats 1 and at 4 are secured to cleats 5, the end slats 2 being also fastened to said cleats and on the inside thereof, as shown. The end slats are further connected and secured by cleats 7. The bottom slats are also 45 fastened to the end slats, as by nails 6. The cover comprises slats 8, three in number in the present instance. They are connected by angle-pieces 9, preferably of sheet metal, secured to their ends as illustrated. Said angle-pieces are fastened to the cleats 7 near 50 their ends by fastenings 10.

By the described construction the cover and the bottom are made narrow, leaving 55 ventilating-openings 11 along their sides adjacent the side edges of the crate. Ventilating-openings are also provided at the end edges

between the slats 3. This means of ventilation is specially important at the bottom of the crate, where the pressure of its contents is greatest and where air could not enter were 60 it not for some provision such as herein described. These openings cannot be closed by floor, pavement, or other support on which the edge of the crate may rest, and they afford ventilation within the angle and 65 at points not usually made so accessible to air. Further, as the cover or bottom does not extend to the crate side edges it is protected to a large extent from blows in lines parallel thereto which are most calculated to 70 affect their fastenings. The narrowness of the cover renders it lighter and less burdensome on its hinge connections when supported thereby. It also enables the use of shorter angle-pieces 9, which constitute the trans- 75 verse connections of the cover-slats. The cover also has the general advantage of being made small and light, as is desirable in any relatively movable or detachable part liable to be broken or misplaced when detached and 80 to require replacement. The angle-pieces 9 differ from others in that they are the sole connection of the cover-slats and together with said slats constitute a separable cover adapted to be placed on a crate by staples or the 85 like, which are potential hinges. The fastenings 10 may be detachable nails, screws, staples, or the like, but preferably nails or staples. They are removable to provide that the cover, with the angle-pieces secured thereto, 90 can be easily removed from the crate and replaced when desired. More than two holes 12 for fastening-nails may be provided in each or either of the two leaves of the angle-piece 9 either for the use of more nails or to provide 95 in case of frequent reuse that the part 9 may be nailed to the cleat at fresh points to insure its hold in the wood.

The cover, which is narrower than the crate and comprised simply of slats joined by 100 the transverse angle-pieces, is comparatively light and easily handled and can be placed entirely within the crate when the latter is stored or shipped empty. To apply the cover, nothing is required but to place it in 105 position and tack the pieces 9 to the cleats 7.

The angle-pieces at their ends near the side of the receptacle may be connected to it by a staple or nail 10^x, substantially as indicated, whereby when the other edge of the cover is 110 freed from its fastening 10 it can be turned on said fastenings. To permit the cover to

swing over, so as to be suspended vertically (or nearly so) on the staples, the hole in the angle-piece is made sufficiently large to permit it to pass along the upper member of the 5 staple and around its curved end, as will be understood from Figs. 4 and 8.

In Figs. 5, 6, 7 is shown a P-shaped staple suitable in many cases for attaching angle-pieces to the receptacle and providing secure 10 pivots for the cover. Though the cover angle-pieces and cover-pivots are illustrated in connection with a crate, they can be used in connection with boxes or other receptacles. Whenever the form of the receptacle or the 15 arrangement of its parts require it, the angle-pieces can have one leaf extended, as indicated at 9^x in Fig. 5, whereby nails or staples that fasten the cover to the receptacle may act as pivots and whereby in some cases 20 the cover can be turned on its pivots nearly or quite two hundred and seventy degrees and be suspended beside the receptacle. In said Fig. 5, 7^x denotes a cleat or other part of a receptacle extended to the side plane of 25 the receptacle. The longer member of a P-shaped staple can be driven into part 7^x, the other member extending through a suitably-placed hole in the angle-piece extension, so that the point 10^v of the staple may then be 30 driven into the rear side. The point 10^v of said P-shaped staple, which may constitute a pivot, is in use situated approximately at right angles to the other point of the staple, which is made of sufficient length to extend 35 through the part 7^x into a slat 2 below the angle-iron and cover, as indicated in Figs. 5 and 7. In this case the cover swings on the staple at the point where it passes through the angle-piece extension 9^x, all other fastenings of the angle-piece to the crate members 40 7 and 2 being removed. It is not material in all cases that the cover should swing on its pivot-staples or the like over the side of the crate as distinguished from its end. If the 45 form of staple shown in Fig. 5 be used, then upon removing the staple or staples at one end the cover to which the angle-plate 9 is fixed can be turned on the staple, the angle-iron sliding around its curved part. As indicated in Fig. 6, the cover would be opened 50 sidewise, the cover, including the angle-irons and slats only, turning on the short member of the staple.

Angle-pieces and staples are well-known 55 devices and are not claimed herein, except in the combinations pointed out in which the

particular operation and advantages set forth are secured.

Having described the invention, what I claim is—

1. In a receptacle, a cover consisting of slats connected by angle-pieces having one leaf fixed thereto, and means for fixing the other leaf to the receptacle said means comprising single-piece fastenings passing loosely 60 through the angle-pieces, a part of said fastenings being adapted to remain stationary, when others are removed, to constitute pivots for the cover.

2. In a receptacle, a cover consisting of 70 slats connected by angle-pieces having one leaf fixed thereto, and means for fixing the other leaf to the receptacle said means comprising removable single-piece fastenings passing loosely through the angle-pieces, a 75 part of said fastenings being adapted to remain stationary when others are removed to constitute pivots for the cover said pivot-fastenings permitting the cover to swing through approximately two hundred and seventy degrees. 80

3. In a receptacle, a cover consisting of slats connected by angle-pieces, the P-shaped staples, and the perforated extensions 9^x of the angle-pieces, said staples each 85 having members entered in the receptacle at right angles to each other and one of said members passing loosely through perforations in said angle-piece extension to permit the angle-piece to turn on a staple member 90 serving as a pivot for the cover.

4. In a crate or the like, the combination of cover-slats, angle-pieces fixed to said slats to connect them, said angle-pieces having each a flange extending below the cover-slats, 95 and fastening means to connect it to said flange and also to the crate below the flange, said means consisting of staples having each one member entered through the angle-piece into a cover-slat and the other entered in the 100 crate below the cover and angle-piece, said staples constituting the sole connection of the cover and crate whereby when part of them are removed the cover can be swung open and depend from the others. 105

In testimony whereof I have signed this specification in the presence of two subscribing witnesses.

WILLIAM W. DAVIS.
